UNITED STATES PATENT OFFICE.

TALBOT G. MARTIN, OF CHICAGO, ILLINOIS, ASSIGNOR TO AUTOMATIC ELECTRIC COMPANY, OF CHICAGO, ILLINOIS, A CORPORATION OF ILLINOIS.

AUTOMATIC OR SEMI-AUTOMATIC TELEPHONE SYSTEM.

1,308,740.

Specification of Letters Patent.

Patented July 1, 1919.

Application filed February 19, 1914, Serial No. 819,678. Renewed October 28, 1918. Serial No. 260,063.

To all whom it may concern:

Be it known that I, TALBOT G. MARTIN, a citizen of the United States of America, and resident of Chicago, Cook county, Illinois, have invented certain new and useful Improvements in Automatic or Semi-Automatic Telephone Systems, of which the following is a specification.

My invention relates to improvements in automatic or semi-automatic telephone systems and has for its object several features of improvement whereby the efficiency of operation of these systems is increased.

Among the objects of my invention is the improved manner of giving a busy signal to an operator in a semi-automatic system when an attempt is made to establish connection with a busy line. This improvement relates to the type of busy signal known as the "flash busy"—that is, a busy signal which is given by the flashing of a supervisory lamp at the operator's position. The feature of my invention is an improved manner of operating this type of signal by intermittent reversals of current which are controlled by the busy signaling machine.

A further feature of my invention relates to an improved manner of disconnecting the ringing current from the called line either during the ringing or non-ringing period.

A further feature of my invention relates to improved means for selecting order wires which extend between operators' positions.

These and other objects of my invention will be more readily understood by reference to the accompanying drawings, in which I have illustrated my invention in connection with automatic switches and cord circuits of well-known types.

40 In the drawings Figures 1, 2 and 3 taken together show a complete circuit connection established between a calling manual substation T and a called automatic substation A'.

Fig. 1 shows the manual substation T, an individual or line switch C, an answering jack equipment F and an A-operator's cord S, together with the automatic order wire selecting apparatus E.

Fig. 2 shows a B-operator's equipment I. Fig. 3 shows an automatic connector switch H, an individual or line switch C' and an automatic substation A'.

The manual substation T (Fig. 1) is an ordinary common battery manual telephone comprising the usual receiver 2, transmit-

ter 3, ringer 4 and condenser 5. At the central office the line of the substation T is provided with the usual multiple jacks J' and in addition terminates in the individual or line switch C.

60 The subscriber's individual switch C (Fig. 1) is of the general type of subscriber's switch shown in British patent to R. W. James No. 26,301 of 1906, being, however, of the particular type disclosed and fully 65 described in British patent to T. G. Martin No. 1419 of 1910.

The master switch D (Fig. 1) is of the same general type as that disclosed in British patent to R. W. James No. 26,301 70 of 1906, being, however, of the particular type disclosed in British patent to T. G. Martin No. 1419 of 1910, above referred to. The function of the master switch, as is well known, is to maintain the plungers of 75 all the idle line switches in position to engage the terminals of an idle trunk line.

The answering jack equipment shown at F (Fig. 1) comprises the usual line relay 21, cut-off relay 22, lamp 23 and jack 24. 80

The cord circuit S (Fig. 1) is a well-known type of cord circuit comprising the usual answering and calling plugs P and P', respectively, inductively connected together through the condensers 25 and 26. The 85 usual supervisory lamps 27 and 28 are shown as controlled by the relays 29 and 30, respectively. By means of the key K the A-operator can connect her talking set O with the cord circuit S and by means of the key K' the calling plug may be disconnected from the answering plug and ringing current from the ringing current generator 31 projected upon said calling plug.

Associated with the operator's head set 95 there is a switch E for the purpose of selecting an idle order wire extending to the B-operator. The switch shown at E (Fig. 1) is the same in general as the subscriber's individual switch C, being somewhat simplified, however, in that it is provided with no line or cut-off relay armatures. This switch belongs to a group which is controlled by a master switch (not shown) similar to the master switch D (Fig. 1).

100 The B-operator's equipment shown in Fig. 2 consists of the usual operator's talking set L and the cord circuit I. This cord circuit comprises a supervisory lamp 182 controlled by a relay 181 connected to the third 110

trunk conductor 106. An impedance 151 is bridged across the cord on the calling side of the condensers in conductors 148 and 149, which bridge is controlled by the polarized 5 relay 32 bridged across the called side of said condensers. This last-mentioned bridge is in turn controlled by a third relay 124. A calling device key K^2 is likewise provided the purpose of which is to connect a calling 10 device indicated by the springs 112 with the trunk line, through the medium of which calling device the operator may interrupt the bridge across the trunk line a desired number of times for each of the digits of the 15 number of the called subscriber to control the automatic switches to set up the proper connection. This calling device may be of any desired type, such, for instance, as that shown in British patent to S. G. S. Dicker 20 No. 29,654 of 1910.

The connector switch H (Fig. 3) is of the same general type of connector switch as disclosed in United States Patent No. 815,176, granted March 13, 1906, to Keith, Erickson and Erickson, the circuits, however, being modified to adapt the switch to operate in a system in which the central office apparatus is controlled by impulses delivered over the two sides of the line in 25 series, and being further modified to operate in accordance with the features of my invention. Among other details, the connector H comprises a bank of contacts arranged in horizontal rows or levels, which 30 contacts are adapted to be engaged by a set of wipers 33, 34 and 35 carried upon a shaft (not shown) which has a vertical movement controlled by the vertical magnet 36 and a rotary movement controlled by the rotary 35 magnet 37. The operations of the various parts of the switch are controlled through the medium of a double-wound line relay 43, said relay being connected with the line through the current-reversing springs of a 40 so-called back-bridge relay 44, through the windings of which latter relay the called line is provided with talking current. The line relay 43 controls the circuit for the slow acting relay 49, which in turn controls a circuit 45 for a second slow acting relay 50 adapted to be connected in series with the operating magnets 36 and 37. This relay 50 controls the circuit of the private magnet 42, which magnet controls the usual side switch 50 comprising the wipers 38, 39, 40 and 41. The release of the switch is controlled by means of the release magnet 46, the circuit of which is controlled by the off-normal springs 47, which springs are adapted to be 55 closed only when the switch shaft has been raised one or more steps from the lowermost position. A second pair of off-normal springs 48 is likewise provided, through which springs a locking circuit for the relay 153 is completed. Connected in series 60 with this relay 153 is a relay 156, the circuit of which is controlled by the slow acting relay 50 in a manner to be hereinafter more fully described. The ringing current is supplied to the called line from the ringing 65 generator R by means of the ringing relay 45 connected in series with an interrupter 136. A ringing cut-off relay 143 is provided for opening the circuit of the ringing relay 45 to thereby cut off the ringing current from 70 the called line. Connected in series with the ringing generator R is a relay 137 which only responds to direct current and which operates in a manner hereinafter described to cut off the ringing current from the line. 75 The circuit connections and the manner of operation of these various relays and magnets will be more fully pointed out in connection with the description of the operation of the connector. 80

Associated with the connector H is a busy signaling machine Q which consists of an induction coil or transformer, the primary winding of which is included in a local circuit with battery and two interrupters, 85 one of high frequency and one of low frequency. This induction coil, as shown, comprises the primary windings 168 and 169 and the secondary windings 171 and 172. The primary windings are connected in series 90 through an interrupter controlled by the pendulum 167 secured to the armature 170 operated by the coils 168 and 169 and this interrupter is connected in series with a second interrupter controlled by the pendulum 166 secured to the armature 161 controlled by a pair of coils 163 and 164. This second interrupter is made slower than the first interrupter, as the pendulum of this interrupter is weighted. Through the medium of these interrupters an intermittent 95 interrupted current is supplied to the primary winding which induces an intermittent alternating current in the secondary winding, whereby when said winding is connected 100 with the subscriber's line an intermittent buzzing sound is heard in the receiver. The armature 161 also controls a pair of contact springs 179 which coöperate in a manner to be hereinafter described to cause a supervisory lamp 28 at the operator's position to be flashed to thus give the operator a busy signal. It will thus be seen that when the busy machine is connected to the line, the calling subscriber will hear the busy tone 105 110 in the receiver and in addition thereto the A-operator will be informed that the called line is busy by the flashing of the supervisory lamp. 115

The subscriber's individual switch C' (Fig. 3) is similar in all respects to the switch shown at C. The automatic substation A' (Fig. 3) comprises the usual receiver 2', transmitter 3', ringer 4' and condenser 5'. Being an automatic substation 120 125

it is also provided with a suitable call-sending mechanism for controlling the automatic switches, which mechanism is represented diagrammatically by a pair of impulse springs 51 and 52 and an impulse wheel 53, which latter may be controlled by a dial provided with finger holes in such a way that the impulse springs may be momentarily separated a number of times corresponding to the respective digits of the number of the called subscriber.

For the purpose of supplying battery current for operating the apparatus and for talking purposes, there are shown the batteries B and B', each having one terminal grounded at G and G', respectively.

A general description of the apparatus having been given, it will now be explained how a connection can be established between the line of substation T and the line of a called substation A'. The number of the called line will be assumed to be 22. Since the apparatus disclosed herein is in general well known in the art, and as it is described in the publications herein referred to, its operation will be explained in a more or less general manner.

When the subscriber at substation T removes his receiver 2 preliminary to making a call, an energizing circuit is closed through the line winding 10 of the line switch C. This circuit extends from ground G² through the springs 54 and 55, conductor 56, substation T, conductor 57, springs 58 and 59 and the line winding 10 to battery B. The armature 60, upon being operated, closes a circuit from ground G² through the springs 54 and 61, pull-in winding 8, auxiliary winding 11 and the springs 62 to battery B. The pull-in winding 8, upon energizing, attracts both the armature 12 and the plunger arm 6. The plunger arm, upon being attracted, forces the plunger which is attached to the end thereof into the bank of trunk terminals to which it has access, forcing the springs 13, 14, 15 and 16 into engagement with the springs 17, 18, 19 and 20, respectively. The engagement of the springs 13 and 16 with the springs 17 and 20, respectively, closes a circuit through the line relay 21, shown at F. This circuit extends from ground G through the lower winding of the relay 21, springs 63, springs 20 and 16, conductor 56, substation T, conductor 57, springs 13 and 17, springs 64 and the upper winding of the relay 21 to battery B. The relay 21, upon energizing, closes a circuit from ground G⁴ through the springs 65 and the springs 18 and 14 to the point 66, thence one branch extends over the conductor 67 to the bush of all multiple jacks associated with the line of the substation T. This guarding potential prevents connection being made with the line of substation T while said substation is calling. Another branch

extends from the point 66 through the holding winding 9 of the line switch C to battery B. This circuit through the holding winding 9 is closed before the armature 60 falls back after the circuit through the line winding 10 is broken by the attraction of the armature 12. The armature 60 does not fall back immediately upon the pulling up of the armature 12, due to the fact that simultaneous with the attraction of the armature 12 is the pulling up of the plunger arm 6, which short-circuits the auxiliary winding 11 by closing the springs 68. This short-circuiting of the winding 11 tends to retard the deenergization of the core, and thus the armature 60 is held in an operated position until enough time has elapsed for the circuit through the winding 9 to be closed, whereby the plunger arm 6 is held in an operated position.

The relay 21, upon energizing, also closes a circuit from ground G⁴ through the springs 69 and lamp 23 to battery B. Upon receiving the signal of the lamp 23 the operator inserts the plug P into the jack 24, whereby the calling subscriber's connection is extended to the cord S and a circuit is closed through the cut-off relay 22 of the trunk and the calling supervisory relay 29 of the cord. The circuit of the relay 22 extends from ground G⁶ through the relay 22, bush of the jack 24, sleeve of the plug P and the resistances 70 and 71 to battery B. A branch of the above circuit extends from the sleeve of the plug P through the lamp 27 and the springs 72 and 73 to battery B. The relay 22, upon energizing, disconnects the relay 21 from the trunk, and because its springs are adjusted so that the springs 74 make contact before the springs 63 and 64 break contact, a new holding circuit is established from ground G⁶ for the winding 9 of the line switch C before ground G⁴ is removed. The deenergization of the relay 21 extinguishes the lamp 23. The relay 29 energizes over the heavy conductors shown and in its energized position maintains the circuit of the lamp 27 open and short-circuits the resistance 71.

The operator then throws the listening key K to connect the talking set with the calling line and upon learning that a connection is desired with one of the subscribers who is called automatically by the B-operator, the operator at the cord S depresses her order wire key 75. The closure of springs 76 and the spring 77 forms a circuit from ground G⁷ through the left-hand winding of the relay 78, springs 77, impedance coil 79, springs 76 and the right-hand winding 125 of the relay 78 to battery B. The springs of the relay 78 are so adjusted that the springs 80 make contact before the springs 81 make contact. Upon the energization of the relay 78 a circuit may be traced from 130

ground G^8 through the springs 80, springs 82, pull-down winding 83, springs 84 and 85 and through the springs on the master switch (not shown) to battery B. An instant later a circuit would be formed from ground G^8 through the springs 81, springs 86 and the relay 87 to battery B. However, the time elapsing between the formation of the above-traced circuits is sufficient for the 10 winding 83 to attract the plunger into the bank of contacts 90 to 95, inclusive. At the same time the springs 86 are separated, thus opening the second circuit above traced. The spring 15 89, upon making contact with the spring 84 and causing same to separate from the spring 85, places the high resistance winding 96 in series with the winding 83, thus reducing the current consumed. Upon the 20 plunger forcing the springs 90 and 92 into engagement with the springs 93 and 95, respectively, the A-operator is connected directly with the B-operator's talking set L (Fig. 2).

25 Should all the trunks be busy battery would be removed from the pull-in winding in the usual well-known manner. When an operator presses the order wire key 75, therefore, the circuit through the pull-in 30 winding 83 will not be formed, due to the absence of battery on the winding 83. An instant later the second circuit through the relay 87 will be closed and the relay 87 will become energized and in so doing open the 35 said first circuit at a second point at the springs 82. Also, the busy tone will be given the operator through the springs 97 and the conductor 97^a leading to a busy machine. When one or more of the trunks 40 become idle and the battery is returned to the pull-in windings, the winding 83 will not be energized on account of the open circuit at the springs 82. Thus it will be seen that should an operator get the busy tone 45 upon pressing an order wire key, it will be necessary that she should release the key and thus deenergize the time relay 78 and then again press the key before she can secure connection with a trunk.

50 It will be seen that as long as the B-operator has her talking set connected at her position, the current flowing through her transmitter will energize the relay 98, which in turn keeps the two sides of the trunk open

55 at the springs 99. In case a B-operator wishes to leave her position, the simple operation of disconnecting her talking set from the trunk leading to said position automatically renders the trunk busy over a circuit 60 from ground G^9 through the left-hand winding of the relay 100, trunk conductor 101, springs 99, trunk conductor 102 and the right-hand winding of the relay 100 to battery B. The relay 100, upon energizing over 65 this circuit, places ground from ground G^{10}

upon the master switch bank contact associated with its trunks, in this way making the trunk busy. At the same time the relay 100 closes the springs 103, said springs being two of a chain which are looped through the relay, which corresponds to the relay 100, in each trunk, and should all the trunks become busy, a circuit is completed through the relay 104, said relay operating to stop the master switch (not shown) and remove 75 battery from the pull-down coils.

Upon receiving an order for a connection over the order wire selected in the manner explained above, the B-operator assigns an idle trunk line to the A-operator, whereupon the A-operator releases the key 75 and inserts the plug P' into the jack 105 of the trunk assigned. Upon the insertion of this plug, a circuit is closed from ground G^{11} through the relay 181, conductor 106, bush of the jack 105, sleeve of the plug P' , lamp 28 and the springs 107 and 108 to battery B. A branch of the above-traced circuit extends from the sleeve of the plug P' through the resistance coils 109 and 110 to battery B. The relay 181, upon energizing, closes the circuit of the lamp 182, and the lamp 28 lights over the above-traced circuit to inform the A-operator that the called party has not yet answered. The B-operator now 80 places the plug P^2 into the jack 111 of a trunk line leading to the connector H and the key K^2 is operated to connect the calling device 112 with the trunk. A circuit is thereby completed extending from ground G^{12} through the lower winding of the relay 43, springs 113 and 114, conductor 115, ring of the jack 111, ring of the plug P^2 , springs 116 and 117, the springs of the calling device 112, springs 118 and 119, tip of the plug P^2 , tip of the jack 111, conductor 120, springs 121 and 122 and the upper winding of the relay 43 to battery B. The relay 43, upon energizing, closes a circuit through the slow acting relay 49, which relay, upon energizing, prepares the circuit of the vertical magnet 36 and opens the circuit of the release magnet 46. When the key K^2 is operated, another circuit may be traced from ground G^{13} through the springs 123 and the relay 124 to battery B. The relay 124, upon energizing, forms a locking circuit for itself from ground G^{11} through the springs 125, springs 126 and the relay 124 to battery B. The relay 124 also prepares the circuit for 100 the polarized relay 32 at the springs 127.

The B-operator now operates her calling device for the first digit 2 of the called number, whereby the springs of the calling device 112 are separated twice momentarily, 105 each time breaking the circuit of the line relay 43 of the connector H. The relay 49 of the connector being slow acting does not deenergize during the momentary interruptions of its circuit by the relay 43, and con- 110

sequently each time the latter relay deenergizes, an impulse is transmitted over the circuit extending from ground G^{14} through the springs 128 and 129, springs 130 and 131, 5 relay 50, vertical magnet 36 and the side switch wiper 38 (in first position) to battery B'. The vertical magnet receives two impulses over this circuit and operates to raise the switch shaft and wipers two steps to a 10 position opposite the second row or level of bank contacts, and at the same time the shaft-controlled contacts 47 and 48 are closed. The slow acting relay 50 is maintained in its energized position continuously 15 while impulses are being transmitted to the vertical magnet through it, and in its energized position closes a circuit from ground G^{15} through the springs 132 and 133 and the private magnet 42 to battery B'. This circuit is broken when the relay 50 deenergizes after the last impulse has been delivered to the vertical magnet. The breaking of said circuit causes the private magnet 42 to deenergize, thus permitting the side switch to 20 pass to second position. In passing from first to second position the side switch wiper 38 transfers the battery connection from the vertical magnet 36 to the rotary magnet 37. The B-operator now operates her calling 25 device for the last digit 2, in response to which the connector line relay operates to transmit two impulses through the rotary magnet 37, whereby the shaft wipers are rotated onto the contacts of the desired line. 30 The circuit of the rotary magnet extends from ground G^{14} through the springs 128 and 129, springs 130 and 131, relay 50, springs 134, rotary magnet 37 and the side switch wiper 38 (in second position) to battery B'. The relay 50 operates in response 35 to the impulses for this digit in the same manner as for the previous digit to cause the private magnet 42 to advance the side switch to third position. By the engagement 40 of the side switch wipers 39 and 40 with their third-position contact points, the line connection is completed with the called line. Upon the engagement of the side switch wiper 41 with its third-position contact 45 point, a circuit is completed through the cut-off winding of the line switch C'. This circuit extends from ground G^{16} through the side switch wiper 41 (in third position), private wiper 34, bank contact 134^a, and the 50 cut-off winding 135 of the line switch C' to battery B'. The cut-off winding of the line switch C', upon energizing, operates to disconnect the line relay from the called substation. The connection of ground G^{16} with the 55 connector private bank contact associated with the called line prevents the called line from being seized by some other connector switch. 60 By the engagement of the side switch wiper 38 with its third-position contact 65 point, the circuit of the ringing relay 45 is closed. This circuit extends from ground G^{17} through the interrupter 136, springs 137^a, ringer relay 45 and the side switch wiper 38 (in third position) to battery B'. 70 The ringing relay is energized intermittently due to the interrupter 136 and operates to disconnect the calling line from the called line and to bridge the ringing current generator R across the called line to signal 75 the called subscriber. The signaling circuit extends from ground G^{18} through the springs 141 and 140, wiper 33, to and through the substation A', wiper 35, springs 138 and 139, relay 137, ringing current generator R and battery B' to ground G' . The condenser 5' at the substation A' will not allow the direct current from battery B to pass over this circuit, and the relay 137 is 80 adjusted not to respond to ringing current. 85 Should the receiver at the called substation be removed while the ringer relay 45 is in an operated position, a circuit for direct current is formed and this flow of direct current energizes the relay 137. The relay 137, 90 upon energizing, closes a circuit which may be traced from ground G^{22} through the springs 48, springs 142, relay 143 and the side switch wiper 38 (in third position) to battery B. The relay 143, upon energizing, 95 opens the circuit of the ringer relay 45 at the springs 137^a and closes a locking circuit for itself through the springs 144 independent of the springs 142. The ringer relay 45 immediately deenergizes upon its circuit being opened and the back-bridge relay 44 then supplies the called substation with talking current. The back-bridge relay 44, upon energizing, reverses the current in the trunk, with results hereinafter explained. Should 100 the called subscriber remove his receiver while the ringer relay 45 is at normal, a circuit will immediately be closed through the back-bridge relay 44. Said relay, upon energizing, will close a circuit from ground G^{22} through the springs 48, springs 145, relay 143 and the side switch wiper 38 (in 105 third position) to battery B'. The relay 143, upon energizing, opens the circuit of the ringer relay 45 at the springs 137^a and 110 closes a locking circuit for itself through the springs 144 independent of the springs 145. 115 After the B-operator has dialed the called number she restores the key K² to normal, and as the key K² is adjusted to make contact with the contacts 146 and 147 before it breaks contact with the springs 118 and 117, the circuit of the connector line relay 43 is transferred from the calling device 112 to a circuit extending from the spring 119, contact 146, polarized relay 32, springs 127, contact 147 to the spring 116 and back to the 120 relay 43. The current flowing through the polarized relay 32 at this time is in such a direction that said relay does not close the 125 130

contact of springs 150. Upon the called subscriber removing his receiver from the hook, the back-bridge relay energizes and operates to reverse the current in the trunk. 5 This reverse current flowing through the polarized relay 32 causes it to be operatively energized and a circuit is closed from ground G¹⁹ (Fig. 1) through the lower winding of the relay 30, spring of key K', ring of the 10 plug P' and jack 105, conductor 148, springs 150, impedance coil 151, conductor 149, tip of the jack 105 and the plug P', spring of the key K' and the upper winding of the relay 30 to battery B. The relay 30, upon 15 energizing, operates to open the circuit of the lamp 28 and shunt the resistance 110. The extinguishing of the lamp 28 notifies the A-operator that the called party has answered. The lamp 182 at the B-board will 20 continue lighted so long as the plug P' is left in the jack 105.

Upon the completion of the conversation the calling subscriber, by hanging up his receiver, opens the circuit of the relay 29, 25 whereby, when said relay deenergizes, the supervisory lamp 27 is lighted. The called subscriber, upon hanging up his receiver, opens the circuit of the back-bridge relay, whereby the back-bridge relay deenergizes 30 and in doing so reverses the flow of current in the trunk back to normal direction. Thus the armature of the polarized relay 32 returns to normal and in so doing opens the circuit of the relay 30, whereby, when said 35 relay returns to normal, the supervisory lamp 28 is lighted. The A-operator, upon seeing both the answering and calling supervisory lamps lighted, knows that disconnection is required and removes the plug P' from the jack 24. Thus the circuit of the 40 relay 22 is opened and, upon the deenergization of said relay, the holding ground G⁶ is removed from the winding 9 of the line switch C, whereupon the winding 9 de- 45 energizes and allows the plunger arm 6 and the armature 12 to return to normal. At the same time the operator removes the plug P' from the jack 105 and in so doing the circuit of the relay 181 is opened, which 50 in turn, upon deenergizing, opens the locking circuit of the relay 124. The relay 124, upon deenergizing, opens the circuit of the line relay 43 of the connector H. The deenergization of the relay 181 also opens the 55 circuit of the lamp 182. The B-operator, upon seeing the lamp 182 extinguished, knows that a disconnect is desired and removes the plug P' from the jack 111. The line relay 43, upon deenergizing, opens the 60 circuit of the relay 49, which in turn, upon deenergizing, closes a circuit from ground G¹¹ through the springs 128 and 129, springs 130 and 152, off-normal springs 47 and the release magnet 46 to battery B'. The release magnet, upon energizing, removes the

retaining pawls from the shaft and its own circuit is opened at the springs 47 when the shaft has reached its lowest position.

It having been explained how the connections are established and released, it will now 70 be explained how a connection is prevented from being made with a busy line, how a busy tone is provided for calling subscriber and how the calling supervisory lamp of the A-operator is flashed to inform her that the 75 number called is busy. If the called number is busy, there will be a guarding potential upon the connector private bank contact associated with that line, just as previously explained. The connector private wiper 34, 80 upon engaging this guarded contact and before the side switch wipers have passed to third position, completes an energizing circuit through the relay 153. This circuit extends from ground at the private bank contact through the private wiper 34, side 85 switch wiper 41 (in second position), springs 154 and 155, relay 153, relay 156, springs 157 and 133 and the private magnet 42 to battery B'. The relays 153 and 156 90 and the magnet 42 energize in series. The relay 153, upon energizing, opens the circuit of the rotary magnet at the springs 134 and also forms a locking circuit for itself from ground G²² through the off-normal springs 95 48, springs 158 and 155, relay 153, relay 156, springs 157 and 133 and the private magnet 42 to battery B. The relay 153, when energized, also forms a circuit extending from the conductor 115 through the springs 159, 100 side switch wiper 39 (in second position) and the condenser 160 to the conductor 120. This circuit is designed to reduce the condenser discharge which would otherwise take place through the calling substation when 105 the back-bridge relay operates in a manner hereinafter explained.

Referring to the busy machine Q, when the armature 161 is in the position shown, a circuit may be traced from ground G²⁰ 110 through the springs 162, pendulum 166, magnet 163, magnet 164 and the resistance 165 to battery B'. Upon the magnets 163 and 164 becoming energized in this manner, the polarized armature 161 operates to 115 open the circuit of the magnets 163 and 164 at the springs 162, and as a result the armature 161 and pendulum 166 are given an oscillatory motion, the speed of which is dependent upon the weight of the pendulum 166 and is preferably quite slow. Each time the armature 161 occupies the position shown, so that the pendulum 166 comes in contact with the ground spring 162, another circuit may be traced from ground G²⁰ 120 through the spring 162, pendulum 166, springs 167 and the magnet windings 168 and 169 to battery B'. The polarized armature 170 then operates in the manner 125 similar to that explained for the armature 130

161 as long as the springs 162 are in contact, except at a much higher rate of speed, the pendulum 167 being lighter than the pendulum 168 and therefore having a higher 5 rate of vibration. From the foregoing it will be seen that the current in the windings 168 and 169 is of an interrupted pulsating nature, and that accordingly an intermittent alternating current will be introduced in the windings 171 and 172. The relay 156 of the connector being energized, this induced current will pass through the windings 172 and 171, condenser 173, lamp 174, resistance 175, springs 176 and 177 of 10 the relay 156, side switch wiper 40 (in second position) to and through the calling substation and through the upper winding of the relay 43 to battery B', and thence back to the winding 172. This busy tone in the 15 receiver will inform the calling subscriber that the called line is busy. Again referring to the busy machine Q, it will be seen that at the time the armature 161 is in an operated position (at which time there is no 20 induced current in the windings 171 and 172), a circuit may be traced from ground G²¹ at the connector through the left-hand winding of the relay 44, springs 178, 177 and 176, resistance 175, lamp 174, springs 179 25 and the resistance 180 to battery B'. The back-bridge relay 44, upon energizing over this circuit, operates to reverse the flow of current in the trunk, whereby the calling supervisory lamp 28 is extinguished, as previously 30 explained. The relay 44 operating intermittently, due to the periodical engagement of the springs 179, causes the lamp 28 to flash intermittently, whereby the A-operator is informed that the called telephone 35 is busy. Should the calling subscriber hang up his receiver, the A-operator would then take down the connection, as previously explained, but should the calling subscriber remain on the line, the A-operator would then 40 communicate with him and inform him that the desired number was busy, whereupon the calling subscriber would hang up and the A-operator would release the connection as before explained.

50 It will thus be seen that I have devised a very efficient system in which the operator is given the busy signal by the flashing of a supervisory lamp, which flashing is controlled by the reversal of current. Furthermore, it will be seen that I have devised very 55 efficient means for disconnecting the ringing current from the called line as soon as the called subscriber answers, whether this is during the ringing interval or during a pause between the ringing intervals. It will furthermore be seen that I have devised very 60 efficient and improved means whereby the A-operator can select an idle order wire extending to the B-operator's position, together with means for preventing this A-

operator from operating her trunk-selecting switch when all the order wires in a group are busy.

While I have illustrated and described my invention in connection with automatic 70 switches of a well-known type, it will, of course, be understood that I do not wish to be so limited, as my invention is adapted for use in connection with many other types of automatic switches. Furthermore, it will 75 be understood that in larger exchanges the well-known form of selector switches can be employed in order to extend the connection from the operator's board to the connector switches. Many other changes and 80 modifications will readily suggest themselves to those skilled in the art and come within the contemplated spirit and scope of my invention.

What I claim as my invention is:—

1. In a telephone system, a calling and a called subscriber's line, means for extending a connection from the calling line to said called line, a visual signal, means for intermittently reversing the current over the connection extending to the called line when the called line is busy, and means operated by said reversal of current for intermittently flashing said signal.

2. In a telephone system, a plurality of 95 subscribers' lines, means including an operator's board for extending a connection from a calling line to a called line, a signal, a polarized relay at said operator's board, means for reversing the current through said 100 polarized relay when an attempt is made to connect with a busy line to thereby operate said relay, and means controlled by the operation of said relay to cause the operation of said signal.

3. In a telephone system, a plurality of subscribers' lines, means including an operator's board for extending a connection from a calling line to a called line, a signal, a polarized relay at said operator's board, 110 means for intermittently reversing the current through said polarized relay when an attempt is made to connect with a busy line to thereby intermittently operate said relay, and means controlled by the intermittent 115 operation of said relay to cause the intermittent operation of said signal.

4. In a telephone system, subscribers' lines, an automatic connector switch for establishing connection with said lines, means 120 including a trunk line for extending a connection to said switch, a visual signal, means for reversing the current over said trunk line when said connector attempts to make connection with a busy line, and means controlled by said reversal of current to cause the operation of said signal.

5. In a telephone system, subscribers' lines, an automatic connector switch for establishing connection with said lines, means 125

- including a trunk line for extending a connection to said switch, a visual signal, means for intermittently reversing the current over said trunk line when said connector attempts 5 to make connection with a busy line, and means controlled by said intermittent reversal of current to cause the intermittent operation of said signal.
6. In a telephone system, a plurality of 10 subscribers' lines, means including an operator's cord circuit and a trunk line extending therefrom for extending a connection to said connector, a polarized relay in said cord, a signal controlled thereby, means for 15 reversing the current in said trunk when said connector attempts to make connection with a busy line, and means controlled by said reversal of current for operating said relay to thereby cause the operation of said 20 signal.
7. In a telephone system, a plurality of subscribers' lines, an automatic connector switch for establishing connection with said lines, means including a trunk line for extending a connection to said switch, a supervisory signal, a back-bridge relay in said connector, means for energizing said relay when said connector attempts to make connection with a busy line, means controlled by 25 30 the energization of said relay for reversing the current in said trunk, and means controlled by said reversal of current for causing the operation of said signal.
8. In a telephone system, a plurality of 35 subscribers' lines, means including an operator's cord circuit and a trunk line extending therefrom for extending a connection to said connector, a polarized relay in said cord, a signal controlled thereby, means for 40 intermittently reversing the current in said trunk when said connector attempts to make connection with a busy line, and means controlled by said intermittent reversal of current for intermittently operating said relay 45 to thereby cause the intermittent operation of said signal.
9. In a telephone system, a plurality of subscribers' lines, an automatic connector switch for establishing connection with said lines, means including a trunk line for extending a connection to said switch, a supervisory signal, a back-bridge relay in said connector, means for intermittently energizing said relay when said connector attempts 50 to make connection with a busy line, means controlled by the intermittent energization of said relay for intermittently reversing the current in said trunk, and means controlled by said intermittent reversal of current for causing the intermittent operation of said signal.
10. In a telephone system, a plurality of subscribers' lines, an automatic connector switch for establishing a connection with 55 said lines, means including an operator's
- cord circuit and a trunk circuit extending therefrom for extending a connection to said connector, a polarized relay in said cord circuit, a signal controlled thereby, a back-bridge relay in said connector, means 70 for energizing said relay when said connector attempts to make connection with a busy line, means controlled by the energization of said back-bridge relay for reversing the current in said trunk, and means controlled by 75 said reversal of current to cause the operation of said signal.
11. In a telephone system, a plurality of subscribers' lines, an automatic connector switch for establishing a connection with said lines, means including an operator's cord circuit and a trunk circuit extending therefrom for extending a connection to said connector, a polarized relay in said cord circuit, a signal controlled thereby, a back-bridge relay in said connector, means for intermittently energizing said relay when said connector attempts to make connection with a busy line, means controlled by 80 85 the intermittent energization of said back-bridge relay for reversing the current in said trunk, and means controlled by said intermittent reversal of current to cause the intermittent operation of said polarized relay 90 to thereby cause the intermittent operation of said signal.
12. In a telephone system, a calling and a called subscriber's line, means for extending a connection from the calling line to said called line, a visual signal, means for reversing the current over the connection extending to the called line when the called line is busy, a busy signaling machine for transmitting a busy signaling current to the calling line, means controlled by said busy signaling machine for intermittently interrupting said reversed current, and means operated by said intermittent reversal of current for intermittently flashing said signal. 100
13. In a telephone system, a calling and a called subscriber's line, means for extending a connection from the calling line to said called line, a visual signal, means for reversing the current over the connection extending to the called line when the called line is busy, a busy signaling machine for intermittently transmitting a busy signaling current to the calling line, means controlled by said busy signaling machine during the interruptions in said busy signaling current for intermittently interrupting said reversed current, and means controlled by said intermittently reversed current for flashing 110 said signal. 115
14. In a telephone system, a plurality of subscribers' lines, means including an operator's board for extending a connection from a calling line to a called line, a signal 120 125

- 5 polarized relay at said operator's board, means for reversing the current through said polarized relay when an attempt is made to connect with a busy line to thereby 50
 6 operate said relay, a busy signaling machine for transmitting a busy signaling current to the calling line, means controlled by said busy signaling machine for intermittently interrupting said reversed current, 70
 10 means operated by said intermittent reversal of current for intermittently operating said relay, and means controlled by the operation of said relay for flashing said signal. 75
 15 15. In a telephone system, a plurality of subscribers' lines, means including an operator's board for extending a connection from a calling line to a called line, a signal, a polarized relay at said operator's board, 80
 20 means for reversing the current through said polarized relay when an attempt is made to connect with a busy line to thereby operate said relay, a busy signaling machine for intermittently transmitting a busy signaling current to the calling line, means controlled by said busy signaling machine during the interruptions of said busy signaling current for intermittently interrupting said reversed current, means operated by said intermittent reversal of current for intermittently operating said relay, and means controlled by the operation of said relay for flashing said signal. 90
 25 16. In a telephone system, subscribers' lines, an automatic connector switch for establishing connection with said lines, means including a trunk line for extending a connection to said switch, a visual signal, means for reversing the current over said 95
 30 40 trunk line when said connector attempts to make connection with a busy line, a busy signaling machine for transmitting a busy signaling current to the calling line, means controlled by said busy signaling machine for intermittently interrupting said reversed current, and means operated by said intermittent reversal of current for intermittently flashing said signal. 100
 35 45 17. In a telephone system, subscribers' lines, an automatic connector switch for establishing connection with said lines, means including a trunk line for extending a connection to said switch, a visual signal, means for reversing the current over said 105
 50 55 trunk line when said connector attempts to make connection with a busy line, a busy signaling machine for intermittently transmitting a busy signaling current to the calling line, means controlled by said busy signaling machine for intermittently interrupting said reversed current, and means controlled by said intermittently reversed current for flashing said signal. 110
 60 65 18. In a telephone system, a plurality of subscribers' lines, means including an operator's cord circuit and a trunk line extending therefrom for extending a connection to said connector, a polarized relay in said cord, a signal controlled thereby, means for reversing the current in said trunk when said connector attempts to make connection with a busy line, a busy signaling machine for transmitting a busy signaling current to the calling line, means controlled by said busy signaling machine for intermittently interrupting said reversed current, means operated by said intermittent reversal of current for intermittently operating said relay, and means controlled by the operation of said relay for flashing said signal. 120
 70 75 19. In a telephone system, a plurality of subscribers' lines, means including an operator's cord circuit and a trunk line extending therefrom for extending a connection to said connector, a polarized relay in said cord, a signal controlled thereby, means for reversing the current in said trunk when said connector attempts to make connection with a busy line, a busy signaling machine for transmitting a busy signaling current to the calling line, means controlled by said busy signaling machine for intermittently interrupting said reversed current, means operated by said intermittent reversal of current for intermittently operating said relay, and means controlled by the operation of said relay for flashing said signal. 125
 80 85 20. In a telephone system, a plurality of subscribers' lines, an automatic connector switch for establishing connection with said lines, means including a trunk line for extending a connection to said switch, a supervisory signal, a back-bridge relay in said connector, means for energizing said relay when said connector attempts to make connection with a busy line, means controlled by the energization of said relay for reversing the current in said trunk, a busy signaling machine for transmitting a busy signaling current to the calling line, means controlled by said busy signaling machine for intermittently interrupting said reversed current, and means operated by said intermittent reversal of current for intermittently flashing said signal. 130
 90 95 21. In a telephone system, a plurality of subscribers' lines, an automatic connector switch for establishing connection with said lines, means including a trunk line for extending a connection to said switch, a supervisory signal, a back-bridge relay in said connector, means for energizing said relay when said connector attempts to make connection with a busy line, means controlled by the energization of said relay for reversing the current in said trunk, a busy signaling machine for intermittently transmitting a

- busy signaling current to the calling line, means controlled by said busy signaling machine during the interruptions in said busy signaling current for intermittently interrupting said reversed current, and means controlled by said intermittently reversed current for flashing said signal.
22. In a telephone system, a plurality of subscribers' lines, an automatic connector switch for establishing a connection with said lines, means including an operator's cord circuit and a trunk circuit extending therefrom for extending a connection to said connector, a polarized relay in said cord circuit, a signal controlled thereby, a back-bridge relay in said connector, means for energizing said relay when said connector attempts to make connection with a busy line, means controlled by the energization of said back-bridge relay for reversing the current in said trunk, a busy signaling machine for transmitting a busy signaling current to the calling line, means controlled by said busy signaling machine for intermittently interrupting said reversed current, means operated by said intermittent reversal of current for intermittently operating said relay, and means controlled by the operation of said relay for flashing said signal.
23. In a telephone system, a plurality of subscribers' lines, an automatic connector switch for establishing a connection with said lines, means including an operator's cord circuit and a trunk circuit extending therefrom for extending a connection to said connector, a polarized relay in said cord circuit, a signal controlled thereby, a back-bridge relay in said connector, means for energizing said relay when said connector attempts to make connection with a busy line, means controlled by the energization of said back-bridge relay for reversing the current in said trunk, a busy signaling machine for intermittently transmitting a busy signaling current to the calling line, means controlled by said busy signaling machine during the interruptions of said busy signaling current for intermittently interrupting said reversed current, means operated by said intermittent reversal of current for intermittently operating said relay, and means controlled by the operation of said relay for flashing said signal.
24. In a telephone system, an A-operator's board, a B-operator's board, a group of order wires extending between said boards, a selecting switch associated with the A-operator's board, an operating magnet therefor, and means for opening the circuit of said operating magnet when all the order wires in said group are busy.
25. In a telephone system, an A-operator's board, a B-operator's board, a group of order wires extending between said boards, a selecting switch associated with the A-

operator's board, an operating magnet therefor, means for opening the circuit of said operating magnet when all the order wires in said group are busy, and means for opening the circuit of said magnet at a second point when the A-operator connects with said switch while all the order wires are busy.

26. In a telephone system, a calling line, a called line, a circuit for connecting the two, said circuit having a manual section and an automatic section, the manual section having manually operated trunk circuits and the automatic section having an automatic progressively movable trunking switch, a battery for supplying current to the said circuits, a busy test circuit for the called line, a busy signal for said manual section, busy signal control means associated with said automatic switch and under the combined control of said test circuit and said automatic switch to reverse the battery supply to the said manual section if the called line is busy for operating said signal and to prevent the operation of said signal if the line is not busy.

27. In a telephone system, a calling line, a called line, a circuit for connecting the two, said circuit having a manual section and an automatic section, the manual section having manually operated trunk circuits and the automatic section having an automatic progressively movable trunking switch, a battery for supplying current to the said circuits, a busy test circuit for the called line, a busy signal for said manual section, busy signal control means associated with said automatic switch and under the combined control of said test circuit and said automatic switch to reverse the battery supply to the said manual section if the called line is busy for operating said signal and to prevent the operation of said signal if the line is not busy, means for automatically applying ringing current to said line when the line is not busy and for intermittently interrupting said ringing current, and means connected in series with the source of said ringing current for disconnecting said ringing current from the line as soon as the called subscriber answers.

28. In a telephone system, a calling line, a called line, a circuit for connecting the two, said circuit having a manual section and an automatic section, the manual section comprising manual trunking equipment, the automatic section comprising an automatic progressively movable trunking switch, a battery for supplying current to the said circuit, a busy test circuit for the called line, means for applying a guarding potential to said test circuit when a called line is busy, a busy signal for said manual section, busy signal control means under the control of said test circuit to reverse the bat-

- terry supply to said manual section if the called line is busy, and means for operating said signal, responsive to said reversal of current, said means comprising a polarized relay.
29. In a telephone system, a calling line, a called line, a circuit for connecting the two, said circuit having a manual section and an automatic section, the manual section comprising manual trunking equipment, the automatic section comprising an automatic progressively movable trunking switch, a battery for supplying current to the said circuit, a busy test circuit for the called line, means for applying a guarding potential to said test circuit when a called line is busy, a busy signal for said manual section, busy signal control means under the control of said test circuit to reverse the battery supply to said manual section if the called line is busy, means for operating said signal, responsive to said reversal of current, said means comprising a polarized relay, means for automatically applying ringing current to the called line if it is idle and for intermittently interrupting said ringing current, and means connected in series with a source of ringing current for disconnecting the same from the line as soon as the called subscriber answers.
30. In a semi-automatic trunking system, an operator's cord and an automatic connector switch for extending a connection between two lines, a battery for supplying current to the connection, a signal for said cord, and means in said connector switch for reversing back and forth the current in said connection for flashing said signal a number of times to indicate that the called line is busy.
31. In a telephone system, the combination with two telephone stations and means including an automatic switch and a trunk line accessible thereto for connecting said stations for conversation, of means at one end of said trunk line for rendering said trunk line busy, and means at the other end of said trunk line for controlling said busying means over the talking conductors of said trunk line.
32. In a telephone system, a trunk line terminating in an operator's position, an automatic switch for seizing said trunk line, means for rendering said trunk line busy to said switch, and operator controlled means for controlling said busying means over the talking conductors of said trunk line.

Signed by me at Chicago, Cook county, Illinois, this 11th day of February, 1914.

TALBOT G. MARTIN.
